[57] CLAIM

The ornamental design for a highchair restraint, as shown and described.

DESCRIPTION

FIG. 1 is a front view of a highchair restraint showing my new design;

FIG. 2 is a rear view thereof;

FIG. 3 is a right side view thereof;

FIG. 4 is a left side view thereof;

FIG. 5 is a top view thereof; and

FIG. 6 is a bottom view thereof; and,

FIG. 7 is a front view of the assembled highchair restraint of FIG. 1.

The crosshatch shading shown in all views is understood to repeat throughout the indicated area.
